UNITED STATES PATENT OFFICE.

LOUIS DE GOLL, OF BALTIMORE, MARYLAND.

COMBINED MATCH AND CIGARETTE BOX.

No. 820,860.

Specification of Letters Patent.

Patented May 15, 1906.

Application filed May 22, 1905. Serial No. 261,641.

To all whom it may concern:

Be it known that I, LOUIS DE GOLL, a citizen of the United States, residing at Baltimore, in the State of Maryland, have invented 5 certain new and useful Improvements in a Combined Match and Cigarette Box; and I do hereby declare the following to be a full, clear, and exact description of the invention, such as will enable others skilled in the art to 10 to which it appertains to make and use the same.

My invention relates to improvements in boxes designed to deliver small articles one at a time. It is especially designed for delivering matches one at a time; but it may be 15 used for other similar purposes, and in the preferred form it is a combined match and cigarette box.

The object of my invention is to produce a simple, economical, and effective device of 20 this class; and with this object in view my invention consists in the construction and combinations of parts, as hereinafter described and claimed.

In the accompanying drawings, Figure 1 is 25 a perspective view of my combined match and cigarette box. Fig. 2 is a cross-section of the same, the dotted lines showing the position assumed as a cigarette is being removed from the box. Fig. 3 is a perspective 30 view of the movable upper end thereof shown bottom side up.

My device is designed to deliver matches or similar small articles one at a time by simply shaking the box. In the preferred form, 35 as shown in Figs. 1 and 2, the box is also adapted to contain cigarettes as well as matches. My invention, however, is not limited to this preferred form, as it may be applied to match-boxes generally and indeed 40 to other boxes for delivering small articles one at a time by simply shaking the box.

a represents a box adapted to contain cigarettes and matches, preferably crescent-shaped to more easily fit in the breast-pocket 45 of the owner. It is provided with a vertical partition *b*, on one side of which matches are arranged and on the other side of which cigarettes appear. To the bottom of the box I have shown applied the ordinary rough paper 50 *c*, on which safety-matches are adapted to be lighted. This, however, is not strictly necessary. The top of the box is closed by a cover *d*, pivoted at *e* therein, and is normally held closed by an elastic rubber band *f*,

which passes over the cover and under the 55 bottom of the box. This elastic band is held in place by the paper *c* on the bottom of the box and by a strip of paper *g*, pasted on the top of the cover. The cover is provided with an inclined groove *h*, which terminates in a hole 60 opposite end the box is cut away, as shown *i*, slightly larger than a match head. At the at *j*, so that by lifting the cover a cigarette may be pulled out by the thumb and finger of the user. To obtain a match, the box is 65 inverted and shaken slightly, whereupon the head of a match falls into the inclined groove *h* and slides down, and the match itself is delivered through the hole *i*.

The box shown in Fig. 1 is preferably 70 made of pasteboard with a rubber band passing around it and fastened to the bottom and cover thereof and curved to fit the pocket of the user.

Having thus described my invention, what 75 I claim as new, and desire to secure by Letters Patent, is—

1. A box provided with a partition dividing it into two chambers, one for the reception of matches, and the other for the reception of cigarettes, a cover pivoted near one end to said box, said cover being provided over the match-holding chamber with a delivery-hole and an inclined trough leading to said hole, and resilient means for holding the 85 cover closed, substantially as described.

2. A box provided with a partition dividing it into two chambers, one for the reception of matches, and the other for the reception of cigarettes, said box being cut away 90 near one corner thereof so that a cigarette may be easily reached, a cover pivoted near one end thereof to the top of said box, and a resilient band secured to said cover and passing around said box, substantially as de- 95 scribed.

3. A crescent-shaped box provided with a partition dividing it into two chambers, one for matches, and the other for cigarettes, said box being cut away near one of its upper corners, a cover pivoted near one end to the top 100 of said box, and an elastic band secured to said box and said cover and passing around them, said cover being provided with a delivery-hole for matches, substantially as de- 105 scribed.

4. In a combined match and cigarette box, the combination of a crescent-shaped box-

body cut away near one of the upper corners thereof, a cover adapted to fit in the open top of said box, said cover being pivoted to said box near one end thereof, and a rubber band passing around said box and said cover, and secured to both of them, substantially as described.

In testimony whereof I affix my signature in presence of two witnesses.

LOUIS DE GOLL.
